UNITED STATES PATENT OFFICE.

DELMAR D. PINKHAM, OF TEXARKANA, TEXAS.

METAL SCREEN.

Application filed December 19, 1925. Serial No. 76,443.

The present invention pertains to a metal screen for doors or windows which has been perfected with the object of providing a simple, durable and economical structure including a metallic frame molding, which can be shipped in knock-down condition and easily assembled on the premises by any handy man, contractor or owner.

A more specific object of the invention is to provide a frame construction for this purpose having mullions which divide the screen into panels, so that in case any part of the netting becomes damaged, one of the panels may be replaced at very little cost instead of covering the entire frame with new netting at nearly the cost of a new screen. The mullions also make the screen more rigid, so that it is less likely to get out of shape or sag. In this construction, the mullions may be arranged in a number of different designs to harmonize with the various styles of windows with which the screens are to be used.

The specific construction of the invention and the advantages thereof will be more fully explained in the following detailed description, which is to be read in connection with the accompanying drawings showing the preferred embodiment of the invention.

In the drawings:

Figure 1 is a front view of an assembled screen constructed according to the invention.

Figure 2 is a rear view thereof.

Figure 3 is a front view, enlarged, of a portion of the screen with portions of the side and end rails broken away and shown in section.

Figure 4 is an enlarged view of an intermediate portion of the screen.

Figure 5 is a detail sectional view taken on the line 5—5 of Figure 4.

Figure 6 is a detail sectional view taken on the line 6—6 of Figure 4.

Figure 7 is a display view of several parts of the invention, about to be assembled.

The invention is shown in connection with a full size window screen having metallic side and end rails 10, each in the form of channels having at one side an inturned flange 11, and at the other side a right angularly disposed flange 12, the edge of which is bent inwardly, as at 13.

The side and end rails 10 have mitered ends, which are adapted to be held in abut-

ting relation to form the corners of the frame. At each corner is a corner piece 14, having branches 15 extending at right angles to each other, and adapted to overlie the adjacent portions of the rails 10 between the flanges 11 and 12. Each rail 10 also is adapted to receive a clamping strip 16, which extends substantially throughout the length of the rail, and clamps the marginal portions of the netting 17 thereto. Each strip 16 is formed with a longitudinal corrugation 18, which fits over a similar corrugation 19 in the corner piece and serves to strengthen the rails, as well as to maintain the same in alignment with the arms 15 of the corner piece.

The side rails 10 are intermediately connected to each other by a cross bar or mullion 20 formed with inwardly inclined opposed side flanges 21, and having at each end a tongue 22, which extends through a slot 23 at the inner side of the rail 10. The channel formed between the side flanges 21 of the mullion is adapted to receive the adjacent edges of the netting 17, which are clamped therein by a partially folded clamping strip 24. This clamping strip may be inserted between the flanges 21 and subsequently spread.

A number of upright mullions 25 may also be inserted between the horizontal mullion 20 and the top and bottom rails. Each of these vertical mullions is similar to the horizontal mullions 20, having inwardly converging side flanges 26 and end tongues 27 adapted to be inserted in slots 28 formed in the sides of the mullion 20. Clamping strips 29, similar to the strips 24, are used in connection with the vertical mullions 25.

Ordinarily the screens will be shipped in knock-down condition, so that the freight charges are much less, and there is less likelihood of the screens being damaged in transit. The assembling of the screens is a very simple matter. The mullions 20 and 25 will first be assembled, then the side and end rails 10 will be put on and connected by the corner pieces 14. The several panels of netting 17 are then laid on and securely clamped by forcing the clamping strips 16, 24 and 29 into the respective channels. The entire assembly forms a rigid and durable structure, which is reinforced by the mullions, so that it will not get out of shape or sag. It is securely held together by the clamping strips which hold the netting, and

in case any part of the netting becomes damaged, it is only necessary to replace the panel wherein the damage has occurred, thus involving only a very little trouble and 5 expense.

While I have shown and described in detail one embodiment of the invention, it is apparent that the relative arrangement of the mullions and the details of their construction may be varied considerably according to the style and size of the window or door in which the screen is to be used. It is to be understood that the invention includes all such modifications as fall within 15 the scope of the appended claims.

What is claimed is:

1. In a metal screen, the combination of an outer rectangular frame having separable side and end rails, a detachable mullion connecting the intermediate portions of two of said rails which are opposite each other, netting covering the panels thus formed, each side rail and each end rail having an inclined overhanging inner flange and an outer flange with an inner return bend, angular corner pieces connecting the side and end rails at the respective corners, clamping strips cooperating with the rail flanges to secure the corner pieces and the outer edges 25 of the netting thereto, and a clamping strip securing the inner edges of the netting to the mullion.

2. In a metal screen, the combination of an outer rectangular frame having separable side and end rails, two of said rails which are opposite each other having opposed slots, a mullion terminating at its ends in tongues which are removably held in the respective slots, netting covering the panels thus formed, each side and each end rail having an inclined overhanging inner flange and an outer flange with an inner return bend, corner pieces connecting the side and end rails at the respective corners, clamping strips 40 operating with the rail flanges, to secure the corner pieces and the outer edges of the netting thereto, said mullion also having overhanging side flanges, and a clamping strip 45 cooperating therewith to secure the inner edges of the netting to the mullion.

3. In a metal screen, the combination of an outer rectangular frame having separable side and end rails, two of said rails which are opposite each other having opposed slots, a mullion terminating at its ends in tongues which fit into the respective slots, netting covering the panels thus formed, each side rail and each end rail having an inclined overhanging inner flange and an outer flange 55 with an inner return bend, angular corner pieces connecting the side and end rails at the respective corners, each leg of each corner piece having a central longitudinal corrugation, clamping strips having longitudinal corrugations fitting over the corrugations of the corner pieces and having side edges extending respectively underneath the inclined overhanging inner flanges and the return bends of the outer flanges to clamp the corner pieces and the outer edges of the netting to said rails, and other clamping strips 60 cooperating with the respective mullions to clamp the inner edges of the netting thereto.

tion, clamping strips having longitudinal corrugations fitting over the corrugations of 65 the corner pieces and having side edges extending respectively underneath the inclined overhanging inner flanges and the return bends of the outer flanges to clamp the corner pieces and the outer edges of the netting, and a clamping strip cooperating with the mullion to clamp the inner edges of the netting thereto.

4. In a metal screen, the combination of a rectangular outer frame having separable 75 side and end rails, said side rails having slots which are opposed to each other, a mullion terminating at its ends in tongues which fit into the respective slots, said mullion and end rails having opposed slots, other mullions disposed at right angles to the first mullion and terminating in tongues which project into the last mentioned slots, netting covering the panels thus formed, each side rail and each end rail having an inclined 80 overhanging inner flange and an outer flange with an inner return bend, angular corner pieces connecting the side and end rails at the respective corners, clamping strips 85 cooperating with the rail flanges to secure the corner pieces and the outer edges of the netting thereto, and other clamping strips securing the inner edges of the netting to the mullions.

5. In a metal screen, the combination of a 95 rectangular outer frame having separable side and end rails, said side rails having slots which are opposed to each other, a mullion terminating at its ends in tongues which fit into the respective slots, said mullion and end rails having opposed slots, other mullions disposed at right angles to the first mullion and terminating in tongues which project into the last mentioned slots, netting covering the panels thus formed, each side rail and each end rail having an inclined 100 overhanging inner flange and an outer flange with an inner return bend, angular corner pieces connecting the side and end rails at the respective corners, each leg of each corner piece having a central longitudinal corrugation, clamping strips having longitudinal 105 corrugations fitting over the corrugations of the corner pieces and having side edges extending respectively underneath the inclined overhanging inner flanges and the return 110 bends of the outer flanges to clamp the corner pieces and the outer edges of the netting to said rails, and other clamping strips cooperating with the respective mullions to clamp the inner edges of the netting thereto.

In testimony that I claim the foregoing as my own, I have hereto affixed my signature.

DELMAR D. PINKHAM.
